UNITED STATES PATENT OFFICE.

BENJAMIN F. AUGUSTINE, OF BUFFALO, NEW YORK.

COMPRESSOR, PUMP, OR THE LIKE.

1,204,535.

Specification of Letters Patent. Patented Nov. 14, 1916.

Application filed September 21, 1911. Serial No. 650,616.

To all whom it may concern:

Be it known that I, BENJAMIN F. AUGUSTINE, a citizen of the United States, residing at Buffalo, in the county of Erie and State of New York, have invented certain new and useful Improvements in Compressors, Pumps, or the like, of which the following is a specification.

The invention relates to new and useful improvements in rotary pumps, or compressors such as are used for pumping liquids, compressing gases or creating a vacuum or the like.

An object of the invention is to provide a rotary pump or compressor having a rotated piston carrier with means for counterbalancing the lateral forces on the piston carrier created by the fluid passing through the pump or compressor.

A further object of this invention is to provide a device of the above character wherein the piston carrier is perfectly balanced with means for counterbalancing the centrifugal force acting on the radial pistons during the rotation of the carrier.

A further object of the invention is to provide a rotary compressor having a piston carrier and radial pistons with means whereby the compressing stroke of the radial pistons covers a region remote from the contact point between the carrier and the wall of the chamber.

A further object of the invention is to provide a rotary pump or compressor with a by-pass connecting the inlet side thereof with the discharge side and a valve for controlling said passage together with devices for controlling the valve whereby, when the demand for the fluid passing through the pump or compressor ceases, the fluid in the pump or compressor will be caused to circulate through the same.

These and other objects will in part be obvious and will in part be hereinafter more fully described.

In the drawings which show by way of illustration one embodiment of the invention, Figure 1 is a transverse vertical sectional view through a rotary pump or compressor embodying my improvements, said view being taken centrally of the pump. Fig. 2 is a longitudinal vertical sectional view centrally through the pump or compressor. Fig. 3 is a transverse vertical section on the line 3—3 of Fig. 2. Fig. 4 is a detail perspective view showing the piston

carrier, the radial pistons, the counterbalancing caps and the operating rings for the radial pistons. Fig. 5 is a detail perspective view of the abutment containing the cylindrical chamber in which the piston carrier rotates. Fig. 6 is a detail perspective view of one of the caps which is connected to the piston carrier and engages the outer face of the abutment. Fig. 7 is a view taken on the line 7—7 of Fig. 2 looking in the direction of the arrow. Fig. 8 is a detail perspective view of the inner ring for one of the radial pistons. Fig. 9 is a similar view of the next adjacent ring for another radial piston. Fig. 10 is a detail perspective view of the next adjacent ring for one of the radial pistons viewed from the opposite side from that of Fig. 9. Fig. 11 is a view similar to Fig. 10 of the outer ring for the fourth radial piston. Fig. 12 is a detail showing the manner of laterally supporting the radial pistons, said view showing the radial piston in end elevation. Fig. 13 is a side elevation of a portion of the abutment showing the outer face of the inlet port in full lines and the inner face thereof in dotted lines. Fig. 14 is a section on the line 14—14 of Fig. 13. Fig. 15 is a sectional detail showing a slightly modified form of intake controlling valve which is used more particularly in connection with the pumping of liquids.

While my device may be used for all the purposes of a rotary pump, the preferred use is for compressing fluids and I will herein-after in the description and claims refer to the same in a general way as a compressor, it being understood, however, that this term is used solely for the convenience of description and not as a limitation.

The rotary compressor consists generally of a frame or casing 1 which is provided with inlet ports and discharge ports controlled by suitable valves. Said casing has a central chamber in which is located an abutment 2 having an eccentrically disposed cylindrical chamber in which is located a piston carrier 3 provided with radial pistons 4, 5, 6 and 7. The piston carrier is held in contact with the wall of the cylindrical chamber and the lateral strain or force of the fluid passing through the chamber on the piston carrier is counterbalanced by caps 8 connected to the piston carrier and engaging the outer face of the abutment. A by-pass connects the inlet side of the compressor with the discharge side and said by-pass is

controlled by a valve which, in turn, is controlled by the pressure of the fluid at the discharge side of the compressor.

I will now describe the various parts referred to above in detail and with particular reference to the drawings.

Casing or frame of compressor.—The casing or frame of the compressor comprises a supporting base 9 upon which is mounted the cylinder 10 which is provided adjacent each end thereof with the usual flanges 11. End plates 12 are bolted to the flanges 11 of the cylinder and said end plates are formed with suitable openings 13 in which are placed bearing sleeves 14 for the main shaft 15 of the compressor. A suitable packing 16 may be placed about the shaft 15 and a flanged sleeve 17 surrounding the shaft 15 holds the packing 16 in place and makes a fluid tight bearing for the rotary compressor. These end plates 12 are also provided on their inner faces with eccentrically disposed bearing hubs 18 which are used for maintaining the radial pistons in proper contact with the inner wall of the abutment, as will be hereinafter more fully described.

The casing 9 is formed with an intake or inlet opening 19. A sleeve 20 is secured to the casing adjacent the opening 19 and serves as a means for directing the fluid to the intake and also as a means for supporting a valve for controlling the intake. The frame or casing 1 on the discharge side of the compressor is formed with a discharge opening 21 in which is threaded a sleeve 22 which is connected at its outer end to a receiving chamber 23. This receiving chamber, when my device is used as a compressor, serves as a storage chamber for the compressed fluids and a suitable pipe may be connected with the receiving chamber so that the fluids stored or compressed therein may be utilized. In order to maintain the compressed fluids in the receiving chamber 23 I have provided a suitable valve 24 which will be described more in detail in connection with the valve mechanism for the compressor.

The inlet side and the discharge side of the compressor are separated from each other by a vertical wall 25 which extends from the base to the abutment 2. This separating wall 25 is formed with a by-pass 26 which extends from one side thereof to the other. A second by-pass 27, indicated in dotted lines in Fig. 1, may also be provided, and these by-passes lead to a common opening in the discharge side of the compressor which opening is controlled by a valve 28 which will be hereinafter more fully described.

Abutment for piston carrier.—The abutment 2 is formed with a central cylindrical chamber 29 which is eccentrically disposed in said abutment. The outer face of the

abutment is cylindrical and concentrically disposed relative to the axis of the driving shaft 15. Therefore, said abutment in effect is cam shaped in cross section. The abutment intermediate its ends is formed with an outwardly extending rib 30 which is shaped so as to fit tightly within the cylinder 10 of the compressor. The lateral strain on the abutment is conveyed through this cylindrical rib to the walls of the cylinder. Between the rib 30 and the outer ends of the abutment said abutment is cut away so as to form a space which extends entirely about the abutment. This space is for the purpose of receiving the counterbalancing caps 8 of the piston carrier which will be hereinafter more fully described. The outer face of the abutment on each side of the central cylindrical rib 30 is formed with a series of pockets or chambers 31 (see Fig. 5). These pockets are separated from each other by ribs 32 which extend longitudinally of the abutment and as herein shown said ribs extend to a point adjacent the outer ends of the abutment. Each of the pockets is closed at its outer end by a circumferential rib 32^a which prevents any leakage from the pockets at the ends of the abutment. Each pocket or chamber 31 is connected with the inner surface of the abutment by a port 33 so that the fluid within the cylindrical chamber of the abutment may pass through the ports 33 and fill the chamber or pockets 31 in the outer face of the abutment. The combined area of the pockets or chambers 31 formed in the outer face of the abutment is substantially the same as the area of the outer face of the rotating piston carrier. This abutment 2, as above noted, engages the upper end of the vertical dividing wall 25 and completes the separation of the inlet side of the compressor from the discharge side thereof so that the fluid passing through the compressor must pass through the cylindrical chamber in the abutment. The fluid passing through the compressor is delivered to the cylindrical chamber through the inlet ports located centrally between the ends of the abutment. The cylindrical rib 30 of the abutment is formed with a circumferentially disposed slot 34. This slot has substantially the same width throughout its length and extends from a point adjacent the vertical wall 25 to a point 35 which is well above the center of the main shaft 5. On its inner face the abutment is formed with a plurality of slots 36, 37 and 38. These slots 36, 37 and 38 are preferably arranged side by side and extend in a circumferential direction about the abutment. The distance from the outer edge of the slot 36 to the outer edge of the slot 38 is of substantially the same width as the rib portion of the abutment and said abutment is cut away 130

from the inner sides of the outer edges as indicated at 39, Fig. 14, to the inner sides of the edges of the slot 34.

Between the vertical separating wall 25 and the outer wall of the compressor on the discharge side thereof is a chamber 40 which is connected with the receiver and this chamber I have termed the main compression chamber. Said main compression chamber 10 is connected with the cylindrical chamber in the abutment by an outlet or discharge port 41 which is similar in construction to the inlet port 34. This discharge port consists of a circumferential slot in the outer face of the abutment extending from the vertical wall 25 to a point 42 which is well above the center of the cylindrical chamber. The inner face of the abutment is provided with a plurality of slots 43, 44 and 45 which are 15 similar to the slots 36, 37 and 38. These slots 43, 44 and 45 are connected with the discharge port 41 in the same manner as the connection between the slot 34 and the slots 36, 37 and 38. It will be apparent, therefore, 20 that the fluid drawn in through the inlet ports may be conveyed through the cylindrical chamber to the discharge ports, thence to the main compression chamber and from the main compression chamber to the receiver. The abutment 2 is also provided with a series of recesses 46 in which are located headed packing or wear blocks 47. These blocks are forced outwardly by 25 springs 48.

35 *Piston carrier and radial pistons.*—The piston carrier 3 has a body portion 49 which is cylindrical in form and is fixedly attached to the main shaft 15 so that as said main shaft is rotated from any suitable source of power, the piston carrier will be rotated thereby. This piston carrier is so proportioned that the outer face thereof is in running contact with the wall of the cylindrical chamber 29 in the abutment 2. Rigidly 40 secured at each end of the body portion 49 of the piston carrier are end plates 50 which project beyond the outer surface of the body portion 49. These end plates form flanges which embrace the end walls of the abutment 2. Said flanges are preferably so proportioned as to lie substantially flush with the outer surface of the ribs 32 and 32^a on 45 the abutment. In order to form a seal between the end wall of the abutment and the end flanges, I have provided the abutment with a circumferential recess 51 in which is located a ring 52 which ring is preferably of metal and is forced outward by any suitable means so as to forcibly contact with the 50 side walls of the projecting flanges 50. These end plates forming the flanges 50 may be made detachable from the body of the piston carrier or one of said end plates may be integral with the piston carrier and the other 55 detachable as shown in Figs. 2 and 4. Lo-

cated in the body of the piston carrier are radial guide-ways 53 which are adapted to receive the radial pistons 4, 5, 6 and 7. These guide-ways in the body portion of the piston carrier also extend into the end plates 50 70 and to the outer edge of the flanges of said plates. The radial pistons also extend through the end plates to the outer faces thereof. The radial guide-ways in the end plates 50 are enlarged as shown at 54 and a 75 hardened steel plate 55 is seated in said enlarged guide-way. On the outer end of the radial piston is a bearing supporting block 56 carrying a series of rollers which bear against the hardened steel plate 55. These 80 rollers are located only on one side of the radial pistons and on the side to take up the lateral thrusts of the piston against the walls of the guide-ways. Each radial piston in its outer contacting face is formed with a 85 groove or grooves 57 in which are located metal strips 58 which may be pressed outward against the wall of the cylindrical chamber 29 and serve to form a proper sealing contact between the radial piston and the 90 wall of the chamber. Said radial pistons are held constantly in contact with the wall of the cylindrical chamber by rings which are connected to the eccentric hubs 18 as will be hereinafter more fully described. 95

100 *Counterbalancing caps for piston carrier.*—Located at each end of the piston carrier is a cap 8 which is in the form of a sleeve having an end wall by which the sleeve or cap may be secured to the end plates 50 of the piston carrier. These caps extend over the flanges of the end plates and over the outer face of the abutment 2 as clearly shown in Fig. 2. The caps are preferably so proportioned as to have a 105 smooth running contact with the outer faces of the ribs 32. The inner edges of the caps are formed with a projecting rib 61 which engages grooves 62 formed in the cylindrical rib 30 in the abutment 2. This rib and groove connection between the caps and the abutment serves to form a sealing joint between the caps and the abutment and prevents leakage of the fluid in the pockets or 110 chambers in the outer face of the abutment. The caps are also so proportioned as to have a smooth running fit with the inner surface of the cylinder. Inasmuch as the caps overlie the chambers or pockets 31 in the abutment they will be subjected to the pressure 115 of the fluid in said chambers. Also, as these caps are rigidly connected to the piston carrier, any lateral force against the caps will be transmitted to the piston carrier. It will readily be seen, therefore, that the lateral forces of the fluid passing through the compressor will be directed against the rotating piston carrier and also, through the ports 33 and the chambers in the outer face of the abutment, said lateral forces will be directed 120 125 130

against these caps which are connected to the rotary piston carrier. Inasmuch as the combined area of the chambers in the outer face of the abutment is substantially the 5 same as the area of the cylindrical face of the piston carrier, and furthermore, as the lateral force against the caps is in an opposite direction from that against the rotating piston carrier, it will be seen that these lateral 10 forces will counterbalance each other and that there will be substantially no lateral force of the piston carrier against its bearings. When a radial piston passes the inlet ports and creates a vacuum the lateral 15 suction force on the piston carrier will be offset by the lateral suction force on the caps connected to the piston carrier. When a radial piston is compressing a fluid in advance thereof, the lateral forces of the fluid 20 exerted against the piston carrier will be likewise exerted against the caps and again said lateral forces will be opposed and counterbalanced. By my construction 25 wherein a series of pockets or chambers are used and a separate port is connected to each chamber, one chamber after another will be thrown into action as the piston carrier rotates and thereby the area on the caps exposed to a given lateral force will 30 be kept substantially equal to the area of the surface on the carrier exposed to said lateral force. The lateral forces on the rotary carrier will, therefore, be perfectly counterbalanced during the entire rotation 35 of the same.

Counterbalancing devices for radial pistons.—The radial pistons are held in running contact with the wall of the cylindrical chamber as above noted by the eccentric 40 hubs 18 at each end of the compressor. Each radial piston is provided with a stem 63 at each end which extends through a radial slot 64 in the caps 8. These stems are preferably rectangular in cross section 45 and fit within cylindrical bearings 65. The bearing 65 for one of the radial pistons is mounted in a lug 66 carried by a ring 67. The bearing 65 for another radial piston is mounted in a lug 68 attached to a ring 69. The ring 69 is formed with a collar 70 which 50 extends on each side thereof. (See Fig. 2.) The ring 67 fits on said collar 70 while the collar 70 fits on the eccentric hub 18. The bearing 65 of another radial piston is 55 mounted in a lug 71 connected to a ring 72 which fits on the collar 70 and the fourth radial piston is connected to a bearing 65 mounted in a lug 73 connected to a ring 74 which also fits on the collar 70. As the 60 piston carrier rotates, these rings will be caused to rotate about the eccentric hubs. These eccentric hubs are concentric with the cylindrical chamber and therefore said radial pistons will be held in contact with the wall of the cylindrical chamber and will 65

slide relative to the piston carrier in the guide-ways formed therefor. Not only do these rings hold the radial pistons in proper running contact with the walls of the cylinder, but said radial pistons through a common collar 70 are connected together. The 70 radial pistons are also oppositely disposed and therefore, the centrifugal force acting on one radial piston through the collar 70 will be offset or counterbalanced by the centrifugal force acting upon the oppositely disposed radial piston. By this overcoming 75 of the centrifugal force operating upon the radial pistons I avoid any great wear between the radial pistons and the wall of the 80 cylindrical chamber. Said pistons are so constructed as to have a smooth running contact with this wall and regardless of the speed of the compressor said radial pistons will be held in free running contact with 85 the wall.

Valve mechanism for compressor.—While my rotary compressor, as above noted, may be used for pumping liquids or for other similar purposes, it is especially adapted for compressing fluids such as a mixture of air and gas which may be utilized in connection with a combustion engine. In order to properly control the supply of air and gas I have provided the inlet port 19 with a 90 controlling valve 75. This valve is formed cone shaped and engages a cone shaped seat in the sleeve 20. The valve stem 76, connected to the valve 75, extends through the outer end of the sleeve 20 and slides freely 95 in the closed end of the sleeve. A spring 77 engages lugs 78 projecting inwardly from the sleeve 20 at one end and engages a collar 79 on the valve stem 76 at its other end. This spring normally holds the valve closed. 100 The suction stroke, however, of the compressor will open the valve and draw through the inlet port 19 the fluid which is to be compressed. At the bottom of the sleeve 20 is an opening 80 through which 110 air may pass to the inlet port 19 when the valve 75 is open. At the upper face of the sleeve are a plurality of ports 81 leading to a chamber 82 which is connected to the supply pipe 83. A liquid fuel such as gasoline, 115 for example, may pass through pipe 83 to the chamber 82. A piston valve 84 normally closes the ports 81. Said piston valve is formed with a plurality of ports 84^a which may be brought into register with the ports 81 in the sleeve 20. These ports in the valve are differently spaced relative to the ports in the sleeve so that as the valve slides first one port and then another will be opened and by varying the size of said ports 120 I am able to gradually open the valve and gradually increase the supply of liquid fuel. The piston valve 84 is connected to the valve stem 76 of the valve 75 by a plate or link 85. This plate or link is located between 125 130

nuts threaded on to the end of the piston valve and also between nuts threaded on to the end of the valve stem 76. By adjusting these nuts the position of the piston valve 5 relative to the valve 75 may be adjusted. In the rotation of the piston carrier on the first part of the suction stroke the valves 75 and 84 will be opened slightly if the piston carrier is rotating slowly and a small amount 10 of air and liquid fuel drawn in through the port 19. The air and the liquid fuel will be intermixed and delivered to the discharge side of the compressor where it will be compressed and delivered to the receiver. Upon 15 an increase of the suction stroke so that an increased amount of air is drawn in, the valve which controls the liquid fuel will be opened a little farther and the proper proportion of liquid fuel given to the compressor to make a mixture of a predetermined richness. The richness of the mixture may be readily varied by adjusting the connection between the valve stem 76 and the piston valve 84.

20 The valve 24 for controlling the compressed gas which passes to the receiver is an ordinary cone shaped valve fitting a cone shaped seat in the sleeve 22. A spring 86 is seated on an inwardly projecting lug carried by the sleeve 22 at one end and at its other end said spring engages a collar 87 carried by the valve stem 88. Said valve stem passes through a spider at its outer end which properly guides the valve so that 25 the compressed fluid in the main compression chamber will open the valve 24 and pass into the receiver 23.

25 The by-pass 26 is controlled as above noted by a valve 28. The sleeve 89 is inserted in the opening through the vertical wall 25 and said sleeve is formed with a seat against which the cone shaped valve rests. A spider 90 is carried by the sleeve 89 and provides a bearing for the stem 91 30 of the valve 28. A spring 92 encircles the stem 91 and at one end bears against the spider while at the other end said spring bears against a piston 93 rigidly carried by the end of the valve stem 91. This piston 35 slides in a small cylinder 94 secured to the end of a sleeve 89 by suitable bolts 95. A pipe 96 connects the receiver 23 with the outer end of the cylinder 94 so that the space between the piston 93 and the head 40 of the cylinder is subjected to precisely the same fluid pressure as the receiver 23. The piston head 93 in area is slightly greater than the area of the valve 28 so that the fluid pressure against the entire valve 28 is 45 less than the fluid pressure against the entire exposed surface of the piston 93. The spring 92, therefore, serves to hold the valve 28 closed. When the pressure of the fluid in the receiver 23 reaches a point so that 50 the pressure against the piston 93 exceeds

the pressure against the valve 28 sufficiently to overcome the tension of the spring 92, then the valve 28 will be open and the fluid in the main compression chamber can then pass through the by-passes in the vertical 55 separating wall 25 to the inlet side of the compressor. This spring can be adjusted so that when a desired degree of compression is obtained in the receiver the valve will automatically shift so as to connect the delivery side of the compressor with the inlet side thereof and said compressor may continue to rotate causing the fluid contained therein to circulate in the compressor with no waste whatever of the fluid. When the 60 by-pass is opened by the shifting of the valve 28 the suction will not of course be sufficient to open the valve 75 and therefore no further fluid will be drawn into the compressor and the circulation noted above 65 takes place.

When my rotary compressor is used purely as a pump for delivering a liquid, the form of the valves may be slightly changed if desired. In Fig. 15 I have shown a modified form of the inlet controlling valve which is specially adapted for use when pumping liquids. It is obvious, however, that the valve shown in Fig. 1 may be used for pumping liquid if desired. In this valve 70 mechanism shown in Fig. 15 the sleeve 97 is formed with a single opening 98 and on the outer end of the sleeve is threaded a supply pipe 99. The valve 100 for controlling the inlet port through the sleeve 97 is similar to the valve 75 and is held normally closed by the spring 101. In connection with the pumping of liquids the receiver 23 may be slightly changed so as to become a compressed air chamber for giving a uniform head to the liquid passing through the pump or compressor.

Operation.—The piston carrier may be rotated as above noted from any suitable source of power. As this carrier rotates the 110 radial pistons are held in running contact with the wall of the cylindrical chamber through the eccentric bearing hubs coöperating with the rings which are in turn connected to the radial pistons. Through the 115 connection of these rings the centrifugal force acting on one radial piston will be counterbalanced by the centrifugal force acting on the oppositely disposed radial piston and therefore said piston carrier and radial 120 pistons will rotate freely in the cylindrical chamber. When the radial piston is passing the inlet ports in the abutment it is idle so far as any drawing in or suction action 125 on the fluid is concerned. As soon, however, as a radial piston passes the upper ends of the inlet ports a partial vacuum will be created in the rear of the piston which will draw in through the inlet valve 75 a certain amount of fluid. The character of the fluid 130

drawn in will of course depend entirely upon the use to which my compressor is put. This fluid drawn in by the radial piston as it continues its forward movement will be 5 trapped between the same and the next succeeding piston and conveyed to the other side of the compressor where it is delivered to the compression chamber and finally to the receiver. The compression of the fluid 10 drawn in by one radial piston is accomplished by the next succeeding piston. Considering the parts as positioned in Fig. 1 the radial piston 7 is just about to complete its compression stroke upon the fluid in advance thereof. The fluid has been forced 15 by the movement of the radial piston through the outlet ports 43, 44 and 45 into the main compression chamber 40. By the term forced I do not mean however that the fluid is rushed through the ports as these 20 ports 43, 44 and 45 are relatively large and the space in advance of the radial piston 7 in the cylindrical chamber and the slots in the abutment together with the main compression 25 chamber all form substantially one compression chamber in which the fluid is being compressed. These outlet ports 43, 44 and 45, leading to the main compression chamber, extend to a point above the center 30 of the compression chamber and as soon as the radial piston 7 reaches the upper ends of the outlet ports the space between the radial pistons 4 and 7 will at once be connected with the space between the radial pistons 6 and 7 35 and also with the main compression chamber. Therefore, the pressure on each side of the radial piston 7 will be equalized and this piston may be considered an idler so far as its action on the fluid is concerned until it 40 passes by the inlet ports on the other side of the compressor and again draws in the fluid to be compressed. As soon as the piston 7 becomes an idler the piston 4 at once begins to compress the fluid in advance thereof 45 and forces the same down into the main compression chamber. By this construction wherein the outlet ports extend to a point well above the center of the chamber it will be seen that the compression stroke of the 50 radial piston covers a region extending from the point A to the point B which is the portion of the cylindrical chamber that is substantially opposite the wall of the abutment. In this region of the compressor all parts 55 of the wall of the carrier are substantially equally spaced from the outer wall of the chamber and, therefore, little or no compression of the fluid is caused by the conformation of the chamber in which the piston 60 moves, but the compression of the fluid is brought about almost solely by the forward movement of the radial piston forcing the fluid into the main compression chamber thus getting in effect the compression 65 accomplished by the right line movement of

the piston and as one piston follows after another there will be a succession of operations which are in effect the same as a continuous right line movement of the piston. It will be apparent, therefore, that in the 70 compression of the fluid there is little or no loss of power due to friction or varying compression on the fluid. In other words, although I use a rotating carrier having a radial piston, which rotating carrier is eccentrically disposed in a cylindrical chamber, I am able to obtain a regular constant compression force upon the fluid. 75

As above noted, when the compression in the receiver reaches a predetermined point 80 the valve 28 controlling the by-pass will be opened and the fluid in the compressor will be caused to circulate in the compressor passing from the delivery side thereof to the inlet side and no further drawing in of 85 fluid will occur while said valve is open and neither will there be any loss of the compressed fluid in the receiving chamber such as occurs when a safety valve is used on the receiver. The operation of my device when 90 pumping a liquid is substantially the same as in compressing a fluid. The liquid is drawn in to the cylindrical chamber through the suction action of the radial piston and the next succeeding radial piston takes up 95 the fluid drawn in and forces it through the cylindrical chamber and out of the delivery side of the compressor.

In my construction wherein the inlet and delivery ports in the abutment extend well 100 above the center of the cylindrical chamber, a considerable portion of the rotating piston carrier will be subjected to the lateral strains or forces in the fluid being compressed. This lateral strain on the rotating 105 carrier will be, however, perfectly counterbalanced by the opposing force of the compressed fluid on the caps which are connected to the rotating carrier as has been above described. Furthermore, the fluid 110 passing out through the ports in the abutment into the chambers in the outer surface of the abutment will form between the outer surface of the abutment and the caps a fluid joint which will tend to cause the caps and the carrier connected thereto to float or run freely on this fluid joint and all lateral strain on the driving shaft is avoided. It will therefore be seen that I have provided 115 a means whereby a portion of the force of the compressed fluid may be utilized to counterbalance all of the objectionable lateral forces or strains on the driving shaft. Furthermore, these caps engaging the outer 120 face of the abutment will embrace the abutment on one side while the rotating piston carrier at its point of contact with the wall of the cylindrical chamber embraces the abutment on the opposite side. The fluid 125 pressure against the cap will therefore tend 130

to maintain said rotating piston carrier in proper running contact with the wall of the cylindrical chamber. I prefer to provide the wall of the cylindrical chamber with a series 5 of longitudinal grooves 101^a and also to provide the abutment with a series of grooves 101. These grooves are short and are staggered and serve to form an effective seal to prevent the escape of the fluid from the 10 delivery side of the compressor to the inlet side of the compressor.

It is obvious that minor changes of the construction and arrangement of parts may be made without departing from the spirit 15 of my invention as set forth in the appended claims.

What I claim is:

1. A rotary compressor including in combination a casing having a cylindrical chamber therein, a rotatable member mounted in 20 said chamber and having contact with the wall of the chamber, a radial piston mounted on said rotatable member, a compression chamber located adjacent the under side of 25 the cylindrical chamber, the latter having a port connecting it with the compression chamber, and an inlet port located on the opposite side of the point of contact between the rotatable member and the cylindrical chamber, said point of contact between the rotatable member and the cylindrical chamber being arranged between said inlet and outlet ports, one of said ports extending from the point of contact between 30 the rotatable member and the cylindrical chamber to a point above the axis of the rotatable member.

2. A rotary compressor including in combination, a casing, an abutment located 35 within said casing and having a cylindrical chamber therein, a rotary carrier within said abutment, said carrier having contact with the wall of the abutment, radial pistons mounted on said carrier, a compression 40 chamber, said abutment having an outlet port connecting the chamber therein with said compression chamber, and an inlet port located on the opposite side of the point of contact between the carrier and the abutment, said inlet port extending from said 45 point of contact to a point above the axis of said carrier, said point of contact between the carrier and the abutment being located between said inlet and outlet ports.

55 3. A rotary compressor including, in combination, a casing having a cylindrical chamber therein, a rotatable member mounted in said chamber, said rotatable member having contact with the wall of the chamber, a radial piston mounted on said rotatable member, a compression chamber, said cylindrical chamber having an outlet port connecting said chamber with said compression chamber, and an inlet port located on 60 the opposite side of the point of contact 65

between the rotatable member and the cylindrical chamber, said inlet port extending from said point of contact to a point above the axis of said rotatable member, said point of contact being arranged between 70 said inlet and outlet ports, and means to automatically control the supply of fluid to the compression chamber.

4. A rotary compressor including, in combination, a casing having a cylindrical chamber therein, a rotatable member mounted in 75 said chamber, said rotatable member having contact with the wall of the chamber, radial pistons mounted on said rotatable member, a compression chamber, said cylindrical chamber having an outlet port connecting said chamber with the compression chamber, and an inlet port located on the opposite side of the point of contact between 80 the rotatable member and the cylindrical chamber, said inlet and outlet ports extending from said point of contact to a point above the axis of said rotatable member.

5. A rotary compressor including, in combination, a casing having a cylindrical chamber therein, a rotatable member mounted in 85 said chamber, said rotatable member having contact with the wall of the chamber, radial pistons mounted on said rotatable member, a compression chamber, said cylindrical chamber having an outlet port connecting said chamber with the compression chamber, and an inlet port located on the opposite side of the point of contact between 90 the rotatable member and the cylindrical chamber, said inlet and outlet ports extending from said point of contact to a point above the axis of said rotatable member, said point of contact being arranged between 95 said inlet and outlet ports.

6. A rotary compressor including, in combination, a casing having a cylindrical chamber therein, a rotatable member mounted in 100 said chamber, said rotatable member having contact with the wall of the chamber, radial pistons mounted on said rotatable member, a compression chamber, said cylindrical chamber having an outlet port connecting said chamber with the compression chamber, and an inlet port located on the opposite side of the point of contact between 105 the rotatable member and the cylindrical chamber, said inlet and outlet ports extending from said point of contact to a point above the axis of said rotatable member, said point of contact being arranged between 110 said inlet and outlet ports.

7. A rotary compressor including, in combination, a casing having a cylindrical chamber therein, a rotatable member mounted in 115 said chamber, said rotatable member having contact with the wall of the chamber, 120

ber, radial pistons mounted on said rotatable member, a compression chamber, said cylindrical chamber having an outlet port connecting said chamber with said compression chamber and an inlet port located on the opposite side of the point of contact between the rotatable member and the cylindrical chamber, said ports extending from said point of contact to a point above the axis of said rotatable member, means for rotating said rotatable member to force a fluid through the compression chamber, and means for utilizing a portion of said compressed fluid for counterbalancing the lateral force of the compressed fluid on the rotatable member.

8. A rotary compressor including, in combination, a casing having a cylindrical chamber therein, a rotatable member mounted in said chamber, said rotatable member having contact with the wall of the chamber, radial pistons mounted on said rotatable member, a compression chamber, said cylindrical chamber having an outlet port connecting said chamber with said compression chamber, and an inlet port located on the opposite side of the point of contact between the rotatable member and the cylindrical chamber, said ports extending from said point of contact to a point above the axis of said rotatable member, means for rotating said rotatable member to force a fluid through the compression chamber, means for utilizing a portion of said compressed fluid for counterbalancing the lateral force of the compressed fluid on the rotatable member, and means for counterbalancing the centrifugal force on said pistons.

40 9. A rotary compressor including in combination, a casing having a cylindrical chamber therein, a rotatable member mounted in said chamber, said rotatable member having contact with the wall of the chamber, a radial piston mounted on said rotatable member, a compression chamber, said cylindrical chamber having an outlet port connecting said chamber with said compression chamber, and an inlet port located on the opposite side of the point of contact between the rotatable member and the cylindrical chamber, said inlet port extending from said point of contact to a point above the axis of said rotatable member, said point of contact being arranged between said inlet and outlet ports.

10. A rotary compressor including in combination a casing having a cylindrical chamber therein, a rotatable member mounted in said chamber and having contact with the wall of the chamber, a radial piston mounted on said rotatable member, a compression chamber located adjacent the under side of

the cylindrical chamber, the latter having a port connecting it with the compression chamber, and an inlet port located on the opposite side of the point of contact between the rotatable member and the cylindrical chamber, said point of contact between the rotatable member and the cylindrical chamber being arranged between said inlet and outlet ports, one of said ports extending from the point of contact between the rotatable member and the cylindrical chamber to a point above the axis of the rotatable member, and means to automatically control the supply of fluid to the compression chamber.

11. A rotary compressor including in combination a casing having a cylindrical chamber therein, a rotatable member mounted in said chamber and having contact with the wall of the chamber, a radial piston mounted on said rotatable member, a compression chamber located adjacent the under side of the cylindrical chamber, the latter having a port connecting it with the compression chamber, and an inlet port located on the opposite side of the point of contact between the rotatable member and the cylindrical chamber, said point of contact between the rotatable member and the cylindrical chamber being arranged between said inlet and outlet ports, one of said ports extending from the point of contact between the rotatable member and the cylindrical chamber to a point above the axis of the rotatable member, and a valved by-pass between the compression chamber and the inlet side of the cylindrical chamber.

12. A rotary compressor including in combination a casing having a cylindrical chamber therein, a rotatable member mounted in said chamber and having contact with the wall of the chamber, a radial piston mounted on said rotatable member, a compression chamber located adjacent the under side of the cylindrical chamber, the latter having a port connecting it with the compression chamber, and an inlet port located on the opposite side of the point of contact between the rotatable member and the cylindrical chamber, said point of contact between the rotatable member and the cylindrical chamber being arranged between said inlet and outlet ports, said inlet and outlet ports extending from the point of contact between the rotatable member and the cylindrical chamber to a point above the axis of the rotatable member.

In testimony whereof I affix my signature in presence of two witnesses.

BENJAMIN F. AUGUSTINE.
